METHOD AND MEANS FOR FORMING
METALLIC BELLows

Edgar C. Stanley, Glen Cove, N. Y., assignor to
Webster Engineering Company, Inc., New York,
N. Y., a corporation of New York

Application July 30, 1932, Serial No. 626,323

17 Claims. (Cl. 153—73)

This invention relates to a method and means for forming circumferentially corrugated tubes or bellows. The method and apparatus here described is particularly applicable to tubes formed of steel, or of material having substantially the characteristics of steel.

A method heretofore employed for forming a circumferentially corrugated tube consisted in pressing the wall of the tube between a pair of externally-tangential dies which therefore engaged the wall at substantially a point, and then providing for relative rotation between the tube and the pair of dies. While this method was found suitable for tubes formed of copper, or material having substantially the characteristics of copper, it was unsatisfactory in the case of steel tubes or tubes formed of material having substantially the characteristics of steel. In the case of tubes made of steel or similar material any attempt to form circumferential corrugations by the method employed in the case of copper tubes resulted in crimping and breaking of the relatively thin metal.

Moreover, the method heretofore employed consisted in stretching the material of the tube over the die which determined the shape of the corrugations, the stretching of the material causing thinning and corresponding weakening of the tube.

It is the principal object of my invention to provide a method and apparatus for forming circumferential corrugations in relatively thin tubes which will be capable of forming a plurality of relatively-deep axially-flexible corrugations in tubes of steel, and of other material having the characteristics of steel as to hardness, ductility, etc., without crimping and without causing undue thinning out and consequent weakening of the material.

Further objects and advantages of this invention will become apparent in the following detailed description thereof.

In the accompanying drawings,

Fig. 1 is a plan view, partly sectioned horizontally, showing my method and apparatus.

Fig. 2 is a section taken on the line 2—2 of Fig. 1.

Fig. 3 is a view similar to Fig. 1 but showing a modified form of my invention.

Fig. 4 is a view similar to Fig. 1 showing another form of my invention.

Fig. 5 is a view similar to Fig. 1 showing a further form of my invention.

Fig. 6 is a view of a completed corrugated tube, with part broken away.

Fig. 7 is a view similar to Fig. 1 but showing the method heretofore employed.

Fig. 8 is a view similar to Fig. 1, showing still another form of my invention.

Fig. 9 is a view similar to Fig. 2, taken on the line 9—9 of Figure 8.

Referring first to Fig. 7, there is illustrated a method heretofore employed for forming circumferential corrugations in tubes. By this method, a mandrel 10 was inserted within the tube 11 and mounted for rotation in a lathe between head-stock H and tail-stock T. Said mandrel carried one element 12 of a pair of dies, the other die 13 being carried by the tool-rest R. It will be seen that the inner and outer dies 15 make substantially point-contact with the tube by reason of being externally tangential to each other, so that as the inner mandrel is rotated, point-contact is made successively around the circumference of the tube. Such point-contact 20 results in crimping, in the case of steel tubes or tubes made of material having substantially the characteristics of steel. Also, it will be seen that as die 13 presses the tube over die 12, the material may be unduly stretched, with consequent thinning and weakening. By my method of forming corrugations I avoid both of these objections to the method now in use.

Referring to Figs. 1 and 2, I have shown an inner mandrel 10' within tube 11, said mandrel 30 being mounted in the lathe for rotation. One of the essential elements of my invention whereby I am enabled to overcome the hereinbefore mentioned objections to the method now in use is disclosed in Figs. 1 and 2 in the die 13'. 35 While the mandrel 10' carries a die member 12', similar to member 12 carried by mandrel 10, I avoid point-contact by employing a die 13' of arcuate construction arranged so that dies 12' and 13' are internally tangential, instead of employing two rollers, such as dies 12 and 13 externally tangential. The arc of die 13' is of substantially the same radius as tube 11 and engages around the tube throughout an arc substantially greater than that necessary to provide point contact. In fact contact may be effected throughout an arc substantially equal to a semi-circle, and thus I obtain line contact instead of point-contact between die 13' and tube 11. The mandrel is sufficiently smaller than the tube to permit 40 withdrawal of the mandrel and its die member 12' after the shallow corrugation 14 has been made. It will be understood that a pair of die members 13' are applied on either side of die 12' so as to form the shallow corrugations 14 as the 45

first step in forming the corrugations. By providing line-contact in place of point-contact heretofore employed, I have found that crimping is avoided regardless of the type of material of which the tube is formed. Steel tubes may be corrugated as readily as copper tubes. The stationary outer dies provide the necessary drag effect, and the friction which would ordinarily be created by such effect is reduced by the use of a 10 lubricant.

When the initial corrugations 14 have been formed in tube 11, the mandrel 10' is replaced by a mandrel 10'' having a narrower die member 12'', to permit the corrugations 14 to be carried 15 deeper and brought closer together. This requires also another set of die-members, similar to 13' but of greater degree of curvature and positioned closer together, to be set up in the tool-rest. As an alternative to providing successive 20 sets of dies 13', each set having the members closer together, I may provide for continuous operation of a single set of die members 13'', as shown in Fig. 3. Here inclined guides 20 are provided, and the members 13'' are operated 25 along said inclines by suitable means such as rack 21 on the dies coaxing with pinion 22 on a shaft 23 journaled in the tool rest 16 and operated by handle 24, to bring the members 13'' closer together as the handle is operated. In 30 the final form the tube is as shown in Fig. 6.

The action as above described consists in bringing the ends of the tube more closely together as a result of folding the material over the dies 12', 12'', instead of stretching the material.

In the forms of invention shown in Figs. 4 and 5, I can avoid the necessity of providing successive mandrels, each with a progressively narrower die member 12. Thus, in the Fig. 4 form 40 I fill the tube with a fluid such as oil, sealing the ends by closures 17. The fluid within the tube thus forms in effect an infinitely adjustable die of a radius equal to the internal radius of the corrugation, and will permit the tube to take 45 any form given to it by the die members 13'.

In the Fig. 5 form I accomplish the same result by coating the mandrel with a layer of rubber 18 whose yielding quality gives the same infinitely adjustable inner die as the fluid in the 50 Fig. 4 form; i. e., the inner die is always of the same radius as the internal radius of the corrugation.

In the Figs. 8 and 9 form of the invention I utilize an inner die member 12a having the same 55 radius as the inside of the tube, so that both inner and outer die members conform to the curvature of the tube along a substantial arc of contact. I am enabled to use such an inner die by reason of the fact that said die is less 60 than semi-circumferential so as to permit its withdrawal after a corrugation has been formed. As the depth of the corrugation increases, successive dies 12a making contact with shorter arcs of the tube are employed. Each die 12a may 65 be formed integral with a shaft 10a fixed at one end in the tail stock T and bearing at its other end in the head stock H. The tube 11 may be supported on an inner cylinder 19 carried by the head stock, the shaft 10a extending through 70 an opening in said cylinder.

In accordance with the provisions of the patent statutes, I have herein described the principle and operation of my invention, together with the apparatus which I now consider to 75 represent the best embodiment thereof, but I

desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having now described my invention, what I 10 claim and desire to secure by Letters Patent is:

1. In a device for forming circumferentially-closed corrugations in a tube, inner and outer die members for cooperating with said tube, one of said die members being so formed as to engage 15 said tube along an elongated circumferential arc thereof, and means for rotating said tube, one of said die members being non-rotatable and said other die member being rotatable.

2. In a device for forming circumferentially-closed corrugations in a tube, inner and outer die members for cooperating with said tube, said outer die member being so formed as to engage 20 said tube along an elongated circumferential arc thereof, and means for rotating said tube, 25 said outer die member being non-rotatable and said inner die member being rotatable.

3. In a device for forming circumferentially-closed corrugations in a tube, inner and outer die members for cooperating with said tube, said 30 die members being so formed as to engage said tube along an elongated circumferential arc thereof, and means for rotating said tube, one of said die members being non-rotatable and said other die member being rotatable. 35

4. In a device for forming circumferential corrugations in a tube, inner and outer die members for cooperating with said tube, one of said die members being so formed as to engage 40 said tube around an arc substantially equal to a semi-circle, and means for relatively rotating said tube and said last-named die member, one of said die members being rotatable.

5. In a device for forming substantially-parallel circumferential corrugations in a tube, 45 inner and outer die members for cooperating with said tube, said tube and die members being internally tangential, one of said die members being of substantially the same radius as said tube, and means for relatively rotating said tube 50 and die members, one of said die members being rotated.

6. In a device for forming circumferential corrugations in a tube, inner and outer die members for cooperating with said tube, said tube 55 and die members being internally tangential, one of said die members being of substantially the same radius as said tube and engaging said tube around an arc substantially equal to a semi-circle, and means for relatively rotating 60 said tube and die members, said inner die member being rotatable.

7. In a device for forming substantially-parallel circumferential corrugations in a tube, inner and outer die members for cooperating with 65 said tube, said tube and die members being internally tangential, said outer die member being of substantially the same radius as said tube, and means for relatively rotating said tube and die members, one of said die members 70 being rotated.

8. In a device for forming substantially-parallel circumferential corrugations in a tube, inner and outer die members for cooperating with 75 said tube, said tube and die members being in-

ternally tangential, said die members being of substantially the same radii as the internal and external radii of the tube, and means for relatively rotating said tube and die members, said 5 inner die member being rotatable.

9. In a device for forming circumferential corrugations in a tube, a plurality of die members for engaging one of the outer and inner surfaces of said tube, a cooperating die member engaging the other of said surfaces of said tube, means whereby said first-named die members may be actuated to vary the distance between them progressively, and means for relatively rotating said tube and die members, said 10 inner die member being rotatable.

10. In a device for forming circumferential corrugations in a tube, a plurality of die members for engaging the outer surface of said tube, a cooperating die member engaging the inner surface of said tube, means whereby said first-named die members may be actuated to decrease the distance between them progressively, and means for relatively rotating said 15 tube and die members, said inner die member being rotatable.

11. In a device for making a bellows by forming substantially-parallel corrugations in a thin-walled tube, inner and outer die members cooperating with said tube, and means for positively rotating one of said die members and thereby drawing said tube frictionally between said die members, one of said inner and outer die members having a circumferentially elongated arcuate contact with said tube.

12. In a device for making a bellows by forming substantially-parallel corrugations in a thin-walled tube, inner and outer die members cooperating with said tube, and means for positively rotating one of said die members and thereby drawing said tube frictionally between said die members, said outer die member having a circumferentially elongated arcuate contact with said tube.

13. In a device for making a bellows by form-

ing substantially-parallel corrugations in a thin-walled tube, an inner rotatable die cooperating with said tube, an outer stationary die cooperating with said tube, and means for rotating said inner die and thereby frictionally drawing said tube between said dies, one of said dies having a circumferentially elongated arcuate contact with said tube. 5

14. In a device for making a bellows by forming substantially-parallel corrugations in a thin-walled tube, an inner rotatable die cooperating with said tube, an outer stationary die cooperating with said tube, and means for rotating said inner die and thereby frictionally drawing said tube between said dies, said outer die having 10 a circumferentially elongated arcuate contact with said tube.

15. The method of making a bellows which includes frictionally rotating a thin-walled tube between inner and outer die members while positively driving one of said die members to rotate said tube and displacing a portion of said tube radially by simultaneous elongated arcuate contact with the other of said die members to form circumferentially-closed corrugations. 20

16. The method of making a bellows which includes frictionally rotating a thin-walled tube between inner and outer die members while positively driving said inner die member to rotate said tube and displacing a portion of said 30 tube radially by simultaneous elongated arcuate contact with the exterior of said tube to form circumferentially-closed corrugations.

17. The method of making a bellows which includes rotating a thin-walled tube between 35 and relatively to inner and outer die members by rotating the inner die member in frictional contact with said tube and displacing said tube radially between said die members to form circumferentially closed corrugations by making 40 elongated arcuate contact with the outer circumference of said tube by one of said die members.

EDGAR C. STANLEY.
